SLIDING DOOR

William J. Henry, Jr., Knoxville, Tenn.

Application April 20, 1950, Serial No. 157,023

8 Claims. (Cl. 296—47)

1

This invention relates to a sliding door which may be used advantageously in conjunction with the bodies of automobiles and other analogous vehicles.

Among the objects, advantages and benefits of the present invention are the following. Vehicles having a door or doors of the indicated character may be more easily parked into more narrow spaces. There is less liability of damage to the door by moving the vehicle when the door is open. The door does not move and project into the path of traffic, or in the line of posts, parked automobiles, and other obstructions. The door is less likely to come completely open during travel as is the case with hinged doors. The door in its open position does not interfere with a person entering or leaving the vehicle.

With the foregoing, other objects and advantages of the invention will appear when the following specification is read in connection with the accompanying drawings, in which:

Fig. 1 is a side view of an automobile showing a door mounted on the body thereof in accordance with the present invention, the door being shown closed.

Fig. 2 is a view similar to Fig. 1, but showing the door moved into the open position.

Fig. 3 is a fragmentary sectional plan view showing a portion of the vehicle body, and illustrating the door in its closed position in full lines, and in a partly open position in dotted lines, and in the fully open position in dot-dash lines.

Fig. 4 is an inside perspective view illustrating certain features of the door mounting with a portion of the door.

Fig. 5 is a sectional view taken approximately on the line 5—5 of Fig. 4.

Fig. 6 is a detail sectional view.

In the drawings, 10 designates the body of an automobile, or other analogous vehicle, having a door 11 mounted for sliding movement between a closed and open position with respect to a door opening 12 in the body 10, in accordance with the present invention, as follows.

Use is made of guide rails, rods or shafts 13 which are arranged in spaced parallel relation to each other, and in parallel relation to the longitudinal axis of the body 10 below the floor. The rails 13 are secured in the stated relationship to the floor at the opposite ends by any suitable means, as indicated at 14. If desired, flat braces 15 are interposed between the rails

13 and are secured thereto, as by welding or otherwise. The braces 15 are disposed at right angles to the rails and help to keep the rails parallel and rigid.

In order to support the door for sliding movement on the rails 13 in paths at a right angle to each other, use is made of a slidable carrier 16. The carrier comprises longitudinal tubular members 17 and transverse tubular members 18 welded or otherwise secured to the members 17 on top of the same and at right angles thereto. Rods 19 are slidably received in the transverse members 18 respectively. A cross bar 20 has its opposite ends secured to the members 18. The inner ends of the rods 19 are connected by a cross bar 21 which extend through longitudinal slots 22 in the members 18 to be clear of the latter in the sliding movement of the rods 19. The longitudinal tubular members 17 slide along the rails 13, respectively. Each of the members 17 has a longitudinal slot 23 therein to accommodate the braces 15 and to be clear of the latter in the forward and rearward sliding movement of the carrier 16.

The door 11 is secured to the outer ends of the rods 19, which latter are disposed on the inside of the door at or near the lower end or base of the door. The door has a hand hold 24 both on the inside and outside.

From the foregoing, it will be understood that the door 11 projects upwardly from the carrier 16. As shown in the drawings, the carrier 16 moves forwardly to bring the door into the open position, and moves rearwardly to bring the door into registry with the opening 12 to be brought into the fully closed position in said opening flush with the body 10. When the carrier 16 is in registry with the opening 12, the door may be moved laterally outward for opening the door and moved laterally inward for closing the door. After the door has been initially moved laterally outward to a partly open position, as shown in dotted lines in Fig. 3, the door may be slid forwardly along the body 10 into its fully open position, as shown in dot-and-dash lines in Fig. 3, and from said position may be slid vice versa into its closed position, as shown in full lines in Fig. 3.

In order to clear the rods 19 in the movement of the door, the body 10 has a slot 25 therein. Opposing strips 26 of resilient and flexible material on the body close the slot 25 to exclude the elements of weather yet enable the movement of the rods in the slot.

A buffer bar 27 on the body 10 prevents the

2

door from possibly scraping or scratching the surface of the body as the door is slid back and forth.

In order to latch the door to the carrier 16 as the door is slid laterally outward, there is provided a spring action latch member or tongue 28 on the cross bar 20 which snaps into a keeper slot 29 in the cross bar 21. Likewise, one of the members 18 has a spring action latch member or tongue 30, thereon which snaps into a keeper slot 31 in one of the braces 15. These means are provided for securing or latching the door in the open position. The door may be provided with conventional latching means for latching it in the closed position.

The arrangement or assembly of parts on which the door is mounted may be enclosed in a suitable housing or shield. Such parts kept properly greased facilitate the sliding movement thereof.

It is to be understood that the door may be moved rearwardly into the open position; that two doors may be used to replace the conventional four doors by making them sufficiently large; and that the invention is not restricted to the details above described, but includes all constructions and modifications coming within the scope of the appended claims.

I claim:

1. The combination with a vehicle body having a door opening, of a door for closing said opening, spaced parallel rails fixed on said body parallel to the longitudinal axis of the body, a carrier slideable along said rails, said carrier having spaced tubular members extending transversely of said axis, and rods slidably received in said tubular members, respectively, and secured to the door at the bottom on the inside thereof, the provision and arrangement being such that the door is mounted for sliding movement transversely and then parallel to said axis into an open position alongside of the body, and vice versa into a closed position in said opening.

2. The combination as set forth in claim 1, and coacting means connected with the carrier and the rods for latching the door in a partly open position.

3. The combination as set forth in claim 1, and coacting means connected with the carrier and said rails to latch the door in the open position.

4. The combination as set forth in claim 1, wherein said body has a slot therein to accommodate the rods so that the latter are clear of the body.

5. The combination with a vehicle body having a door opening, of a door for closing said opening, spaced parallel rails fixed on said body parallel to the longitudinal axis of the body, transverse braces connected with the rails between the same, a carrier comprising spaced parallel longitudinal tubular members and spaced parallel transverse tubular members integral with the longitudinal tubular members, said longitudinal tubular members being slideable along said rails so that the carrier is slideable in opposite directions parallel to said axis, said longitudinal tubular members having lengthwise slots

therein to accommodate and clear said braces, rods slidably received in said transverse tubular members, respectively, said rods being secured to the door at the bottom on the inside of the door, and a cross piece connecting the inner ends of the rods, said transverse tubular members having lengthwise slots therein to accommodate the cross piece so that the latter is clear of said transverse tubular members, the provision and arrangement being such that the door is mounted for sliding movement transversely and then longitudinally with respect to said axis into an open position alongside of the body, and vice versa into a closed position in said opening.

15 6. The combination as set forth in claim 1, wherein said body has a slot therein to accommodate the rods so that the rods are clear of the body, and opposed resilient flexible strips on the body which seal the slot, but which yield to the movement of the rods as the door is being moved along the body.

20 7. The combination with a housing having a door opening, of a door for closing said opening, guide members fixed with relation to said housing, a carrier mounted on said guide members for movement along the housing, and means on the door near the bottom and at the inside thereof which slidably cooperates with transversely extending means on the carrier by which the 25 door is mounted on the carrier for movement therewith and lateral movement with respect thereto, the provision and arrangement being such that the door may be moved laterally of the housing and then along the same into an open position, and vice versa into a closed position in said opening.

30 8. The combination with a vehicle body having a door opening, of a door for closing said opening, a guiding structure fixed on said body, a carrier having guided movement on said structure 40 lengthwise of the body, and spaced rods which extend laterally inward from the door slideable in means on the carrier whereby the door is supported on the carrier for movement sidewise in relation to said body, the provision and arrangement being such that the door is mounted for movement transversely to said axis and then parallel to said axis into an open position, and vice versa into a closed position in said opening.
